ROLLER CATCH

Leonard Rosenblum, Hillside, N. J., assignor to
Star Metal Products Co., Brooklyn, N. Y., a
partnership

Application April 8, 1952, Serial No. 281,081

6 Claims. (Cl. 292—75)

1

This invention relates to roller catches of the type, which includes a spring-pressed roller and is commonly used with a strike as a latch for an interior door. More particularly, the invention is concerned with a novel roller catch made of a few parts which can be produced by simple manufacturing operations and can be readily assembled to form the catch. The new roller catch operates smoothly without sticking, and it is subject to little wear and not liable to be damaged in use.

The roller catch of the invention comprises a housing of channel section having a closed rear end and laterally extending ears, by which it can be attached to a door, for example. A slide of channel section is mounted in the housing for longitudinal movement and the slide extends out of the front end of the housing and carries a roller mounted for free rotation on a pin secured in the side walls of the slide. The slide is provided with laterally extending lugs received in slots in the side walls of the housing and guiding and limiting the movement of the slide. The slide is urged to its extreme outer position by a spring bearing against the slide and the rear wall of the housing.

For a better understanding of the invention, reference may be made to the accompanying drawing in which

Fig. 1 is a view of the new roller catch in perspective;

Fig. 2 is a sectional view of the roller catch on the line 2—2 of Fig. 3;

Fig. 3 is a sectional view on the line 3—3 of Fig. 2;

Fig. 4 is a sectional view on the line 4—4 of Fig. 3; and

Fig. 5 is a view in perspective of the slide of the catch.

The roller catch of the invention comprises a housing generally designated 10 and shown as of inverted U-section. The housing includes side walls 11 lying parallel to each other and a rear end wall 12 between the side walls, the side and end walls being integral with a top wall 13. The front end and inner side of the housing, that is, the end from which the slide protrudes and the side which is attached to the door or other surface, are open and the housing is provided with ears 14 extending outwardly in a plane from the lower edges of its side walls. The ears are formed with slots 14a for receiving screws 15, by which the roller catch is attached to a door D, for example. The side walls 11 of the housing are formed with aligned longitudinal slots 11a.

2

A slide generally designated 16 is mounted within the housing and projects outwardly through the open end thereof. The slide is of inverted U-section and includes a top wall 17 and parallel side walls 18. A pin 19 is mounted in openings in the side walls 18 near the outer ends thereof and outside the housing and a roller 20, which is preferably made of rubber, is mounted for free rotation on the pin. The ends of the pin 19 are headed, as indicated at 19a, to hold it firmly in place.

Toward the rear end of the slide, the side walls are of reduced width and each wall is provided with an integral lug 21, which is receivable in a slot 11a in one of the side walls 11 of the housing. About midway between the ends of the top wall of the slide, a tongue 22 is struck inwardly therefrom and the free end 22a of the tongue is bent toward the rear end of the housing. A coil spring 23 lies within the slide and bears at its forward end against tongue 22, the spring encircling the end 22a of the tongue. A tongue 24 is struck inwardly from the rear end wall 12 of the housing and the rear end of the spring bears against the rear end wall 12 and is caught behind tongue 24, so that the spring is properly centered.

As is shown in Figs. 3 and 4, the width of the slide 16 from the plane of the lower faces of lugs 21 to the plane of the lower surfaces of the side walls 18 is less than the distance from the plane of the lower surfaces of slots 11a in the side walls of housing 10 to the plane of the lower faces of ears 14. As a consequence, the slide is supported by lugs 21 in slots 11a with the inner end of the slide spaced from the surface, to which the roller catch is attached, and, as the slide moves in and out of housing 10, it can not tilt sufficiently to bite into or damage the surface. The slide, accordingly, moves in and out of the housing freely and with little friction.

The housing and slide are made from sheet metal and the housing is formed in a single stamping operation. At the completion of this operation, the side walls 11 of the housing lie sprung outwardly to a slight extent. The slide is made in a single stamping operation and it is completed by the mounting of the pin and roller thereon. To assemble the roller catch, the spring is inserted into the housing and its rear end is caught behind tongue 24. The slide is then inserted into the housing with the end 22a of its tongue 22 entering the front end of the spring. Although the overall width of the slide across tongue 21 is greater than the distance between walls 11 of the housing of the completed slide,

the insertion of the slide into the housing can be accomplished because the side walls 11 of the housing are sprung outwardly, as described. After the slide has been inserted into the housing against the resistance of the spring and the lugs 21 are aligned with slots 11a in the side walls of the housing, the side walls 11 are bent toward each other until they lie parallel. As a result of this operation, the lugs 21 on the slide enter the slots 11a and the slide is held positively within the housing, although it is permitted a longitudinal movement equal to the difference between lengths of slots 11a and lugs 21.

In the use of the new roller catch, the slide is forced inwardly against the compression of the spring when the roller rolls over the strike. As the lugs 21 on the slide make contact over relatively long areas with the walls of slots 11a of the housing, the cooperation of these parts insures that the movements of the slide in opposite directions will be along a rectilinear path and the slide cannot tilt sufficiently to cause either end thereof to be moved to a position beyond the plane of the inner side of the housing. Hence, the slide cannot bite into or engage the surface 25 to which the roller catch is attached and will always move freely without any sticking or binding.

I claim:

1. A roller catch which comprises a housing 30 having a top, parallel side walls, and a rear end wall, the front end and inner side of the housing being open and the side walls having aligned longitudinal slots, a slide of channel section within the housing and having integral lugs extending 35 outwardly from its side walls and entering the slots, one end of the slide projecting through the open front end of the housing and the bottom of the slide lying inwardly from the plane of the inner side of the housing, a pin mounted in openings in the side walls of the slide, a roller 40 freely rotatable on the pin and projecting beyond the outer end of the slide, and a spring engaging the rear end wall of the housing and the slide and urging the slide out of the housing, the slots 45 and lugs being positioned inwardly from the slide from the point of mounting of said pin therein and the lugs being elongated in the direction of the 50 sliding movement of the slide and forming a guiding support for the slide during such movement.

2. A roller catch which comprises a housing having a top, parallel side walls, and a rear end wall, the front end and inner side of the housing being open and the side walls having aligned longitudinal slots, a slide of channel section within the housing and having integral lugs extending outwardly from its side walls and entering the slots, one end of the slide projecting through the open front end of the housing and the bottom of the slide lying inwardly from the plane of the inner side of the housing, a pin mounted in openings in the side walls of the slide, a roller freely rotatable on the pin and projecting beyond the outer end of the slide, a seat 60 formed on the slide and lying between the side walls and offset from the wall connecting them, and a spring engaging the seat on the slide and the rear end wall of the housing and urging the slide out of the housing, the slots and lugs being positioned inwardly from the slide from the point of mounting of said pin therein and the lugs being elongated in the direction of the sliding movement of the slide and forming a guiding support for the slide during such movement.

3. A roller catch which comprises a housing having a top, parallel side walls, and a rear end wall, the front end and inner side of the housing being open and the side walls having aligned longitudinal slots, a slide of inverted U-section within the housing and having integral lugs extending outwardly from its side walls and entering the slots, one end of the slide projecting through the open front end of the housing and the bottom of the slide lying inwardly from the plane of the inner side of the housing, a pin mounted in openings in the side walls of the slide, a roller freely rotatable on the pin and projecting beyond the outer end of the slide, a tongue struck inwardly from the outer wall of the slide and having an end extending toward the rear end wall of the housing, and a spring having one end engaging the tongue and encircling said end thereof and its other end engaging the rear wall of the housing, the spring urging the slide out of the housing, the slots and lugs being positioned inwardly from the slide from the point of mounting of said pin therein and the lugs being elongated in the direction of the sliding movement of the slide and forming a guiding support for the slide during such movement.

4. A roller catch which comprises a housing having a top, parallel side walls, and a rear end wall, the front end and inner side of the housing being open and the side walls having aligned longitudinal slots, a slide of inverted U-section within the housing and having integral lugs extending outwardly from its side walls and entering the slots, one end of the slide projecting through the open front end of the housing and the bottom of the slide lying inwardly from the plane of the inner side of the housing, a pin mounted in openings in the side walls of the slide, a roller freely rotatable on the pin and projecting beyond the outer end of the slide, a tongue struck inwardly from the outer wall of the slide and having an end extending toward the rear end wall of the housing, a tongue struck inwardly from the rear end wall of the housing and aligned with said end of the tongue on the slide, and a spring having one end engaging the tongue on the slide and encircling said end of said tongue, the rear end of the spring bearing against the rear end wall of the housing and being caught behind the tongue struck therefrom, the spring urging the slide out of the housing, the slots and lugs being positioned inwardly from the slide from the point of mounting of said pin therein and the lugs being elongated in the direction of the sliding movement of the slide and forming a guiding support for the slide during such movement.

5. A roller catch which comprises a housing of inverted U-section having a closed rear end, the front end and inner side of the housing being open and the side walls having aligned longitudinal slots, ears extending outwardly in a plane from the lower edges of the side walls of the housing, a slide of inverted U-section within the housing having integral lugs extending outwardly from its side walls and entering the slots to support the slide for longitudinal movement with the lower edges of its side walls above the plane of the ears, the slide projecting through the front end of the housing, a pin mounted in openings in the side walls of the slide, a roller freely rotatable on the pin and projecting beyond the outer end of the slide, and a spring engaging the rear end wall of the housing and the slide and urging the slide out of the housing, the slots and lugs being

positioned inwardly from the slide from the point of mounting of said pin therein and the lugs being elongated in the direction of the sliding movement of the slide and forming a guiding support for the slide during such movement.

6. A roller catch which comprises a housing having a top, parallel side walls, and a rear end wall, the front end and inner side of the housing being open and the side walls having aligned longitudinal slots, a slide of channel section within the housing and having integral lugs extending outwardly from its side walls and entering the slots, one end of the slide projecting through the open front end of the housing and the bottom of the slide lying inwardly from the plane of the inner side of the housing, said lugs being elongated in the direction of the sliding movement of the slide and forming the sole means for supporting the slide with the inner side spaced inwardly from the plane of the inner side of the housing and the width of the lugs relative to the width of the slots being such as to prevent such

tilting of the slide as would cause either end thereof to be moved to a position outwardly beyond the plane of the inner side of the housing, a pin mounted in openings in the side walls of the slide, a roller freely rotatable on the pin and projecting beyond the open end of the housing and the outer end of the slide, and a spring normally urging the slide in a direction to move it outwardly of the housing.
